CYLINDER HEAD LIFTING AND HANDLING
DEVICE

Hugh T. McCullough, Marshall Hall, Md., assignor of one-half to Richard L. Eacho, Washington, D. C.

Application August 4, 1939, Serial No. 288,441

5 Claims. (Cl. 254—2)

This invention relates to cylinder head lifting and handling devices and it has for its object the provision of a novel type of portable jack dimensioned and arranged to operate under certain unusual conditions which exist in the more modern types of automobiles, all as will be more fully set forth.

In the drawing,

Fig. 1 is a side elevation of a device constructed 10 in accordance with the invention;

Fig. 2 is a horizontal, sectional view upon line 2—2 of Fig. 1;

Fig. 3 is a side elevation of a cylinder head of the character described having a central stud 15 with which the lift-arm of the device may be engaged, and

Fig. 4 is a view like Fig. 3 but showing a cylinder head having studs at the end but not at the center, and the manner of attaching the device 20 of my invention to a cylinder head of that character.

Like numerals designate corresponding parts in all of the figures of the drawing.

In the drawing, 5 designates a longitudinally 25 extending beam which may be in the form of an I-beam and which, together with the two transversely extending end bars 6 and 7, constitute a base. This base is mounted to roll upon caster wheels 7^a, there being one of said caster 30 wheels at each end of each of the transverse bars 6 and 7. A vertical standard 8 is provided with a suitable flange 9 at its lower end, said flange being bolted or otherwise secured to the beam 5. Arms 10 and 11, which may be secured to the 35 standard 8 in any suitable way, such as by being welded or brazed, terminate in an upstanding arm 12. A pair of links 13 and 14 are pivoted at their lower ends to the arm 12 and in turn pivotally support the rear end of an elongated lever 15. The outer or free end of this lever terminates in the depressed portion 16 which lies at a materially lower level than the main body of the lever. The terminal end of this lever carries a reduced or flattened portion 16^a having an 40 opening therethrough for the reception of the central stud 17 (see Fig. 3) of a cylinder head 18 of an automobile engine, the body of said engine being indicated in dotted lines at 19. The upper end of the standard 8 is provided with a flange 45 20 which constitutes the seating for the base of a small or relatively short throw fluid or hydraulic jack 21, the operating handle of which is indicated at 22. The movable member or stem 23 of the jack is provided with a rounded head 24. The 50 under side of the lever 15 carries a wear and

centering plate 25, the under face of which is of concave formation to conform to the shape of the head 24 of the stem 23.

The purpose of arranging the parts in the manner described and the important advantages flowing therefrom will be best appreciated if a clear understanding is had of the conditions under which a mechanic must work on some of the later type automobiles. In the older type automobile it was possible to completely remove the 5 sides as well as the tops of the hood. In the later type of automobiles the side panels are made separate from the tops of the hoods and in the ordinary servicing of the automobiles only the tops of the hoods are lifted; the sides are not 10 lifted. It is quite a task to remove the side panels and the mechanic seek to avoid the necessity for doing so wherever possible. However, with the side panels left in place the space through which the cylinder head may be removed becomes so 15 restricted that it is very difficult for a mechanic to get to and remove the cylinder head. For the same reason it is very difficult to get the cylinder head back in place. The latter task is rendered additionally difficult because in some types 20 of automobiles the valve push rods, of which there are 12 in a 6 cylinder engine, extend upwardly and into openings formed in the cylinder head. The difficulty of trying to support the weight of the cylinder head while getting all of these push 25 rods aligned with the openings has been so great that the mechanics have been forced to go to the considerable work of removing the push rods before trying to replace the cylinder head. In removing a cylinder head and replacing the same 30 with the device of my invention the wheeled frame or base is rolled in to lie beneath the automobile with the standard 8 disposed close to or against the front fender indicated in dotted lines at 26. At the time of this inward movement the lever 15 will be elevated by jack 21 until the depressed end 16 clears the fixed side panel 27 of the hood and which panel it is desired to leave in place. After the depressed portion 16 has cleared the side panel of the hood 35 the jack 21 is manipulated to lower lever 15 until the opening of the reduced portion 16^a may be engaged with the stud 17. A nut 17^a is then 40 screwed upon the upper end of said stud with the result that when the lever 15 is elevated by the 45 manipulation of the jack the cylinder head will be lifted from the engine 19. By proper manipulation of the jack to elevate the cylinder head while rolling the base outwardly upon its wheels 50 55 the cylinder head may be carried outwardly 55

through the relatively restricted opening at *a* which lies between the top of the hood *h* and the side panel *27* and this result may be achieved without interference by the tie-rods which lead from the dash to the radiator and the positions of which have been indicated in dotted lines at *t*. It will be observed that the jack is supported directly above the standard *8* so that this standard takes the direct thrust of the jack. This standard is in turn supported directly above the front cross-bar *6* and the fact that the standard *8* is disposed directly over said bar resists any tendency of the structure to tip when load is brought thereon under the action of the jack in lifting the cylinder head. The co-acting arcuate surfaces between plate *25* and head *24* insures against any possibility of the lever *15* slipping off of head *24*, while the provision of the hinged links *13* and *14* permits plate *25* to find its proper seating upon said head. Hydraulic or fluid jacks of the character illustrated are too well known to require detailed illustration. It suffices to say that manipulation of handle *22* pumps a pressure fluid against stem *23* to thrust the stem outwardly, and upwardly. When it is desired to lower the stem a screw indicated at *21a* may be turned to release the pressure fluid and permit the stem to descend. This descent of the stem may be rendered exceedingly slow by very slightly opening the valve constituted by the screw *21a*. This is of much utility when replacing the cylinder head because the cylinder head may be caused to descend very slowly while leaving both hands of the operator free to align the valve push rods (not shown) with the holes in the cylinder head. This saves the mechanic the very considerable work of removing and afterward replacing these push rods. If the operator experiences any difficulty in getting the push rods aligned he can instantly interrupt the descent of the cylinder head by closing valve *21a* and the head will be left suspended upon lever *15* until the necessary positioning of the push rods has been effected. By supporting the cylinder head in the manner shown it may be swung in a horizontal plane to lie at any angle with respect to bar *15* that will be most effective in getting the cylinder head into or out of position upon the engine and since no lock nut is employed on stud *17*, a slight tipping or rocking may be given the cylinder head in working it out of the hood.

The structure illustrated in Fig. 4 differs from that illustrated in Fig. 3 only in the provision of an adapter bar *28* that is provided with a plurality of holes *29*, a pair of which may be engaged with end studs *30* of a cylinder head which has no central stud. In this case a central bolt *31* traverses bar *28* and the opening of extension *16a* of bar *15*, said bolt receiving a nut *17b* by which bar *15* is held in connected relation to bar *28*. I am aware of the fact that various types of wheeled jacks have heretofore been proposed for lifting and transporting devices of various kinds. However, as far as I am aware I am the first to provide a jack in which a simple and inexpensive short throw hydraulic jack is used to compound the movement of a lever adapted to span the relatively wide fender of an automobile and to enter the relatively constricted space at *a* and engage the cylinder head at such a low point that the subsequent movement of the jack, along with its capacity for bodily outward travel may be utilized to remove the cylinder head through such constricted space while

avoiding interference with the radiator tie-rods or other overhead parts.

The invention is not limited to the precise construction set forth but includes within its purview whatever changes fairly come within either the scope or the spirit of the appended claims.

Having described my invention, what I claim is:

1. A device for lifting and handling the cylinder heads of automobile engines, comprising a wheeled base adapted to roll in beneath an automobile, a standard at the outer end of said base, a bracket upon said standard which projects outwardly beyond said standard in the direction of the length of said base, a relatively small short throw jack supported upon the top of and in alignment with said standard, a lever extending in the direction of the length of the base above the top of said jack, means for pivoting the outer end of said lever to said bracket, a member carried by the lever against which the stem of the jack thrusts, said stem and said member being complementally formed to resist lateral movement of the lever with respect to the stem, a downwardly extending depressed portion at the outer end of said lever, and cylinder head engaging means at the outer end of said depressed portion of a nature to suspend and swivel a cylinder head from the underside of the end of said depressed portion.

2. A device for lifting and handling the cylinder heads of automobile engines, comprising a wheeled base adapted to roll in beneath an automobile, a vertical standard adjacent the outer end of said base, a bracket upon said standard which projects outwardly from the face of said standard in the direction of the length of said base, a relatively small short throw jack supported upon the top of and in axial alignment with said standard, a lever extending in the direction of the length of the base above the top of said jack, means for pivoting the outer end of said lever to said bracket, a member carried by the lever against which the stem of the jack thrusts, said stem and said member being complementally formed to resist lateral movement of the lever with respect to the stem, and said stem being also in axial alignment with the standard, a downwardly extending depressed portion at the outer end of said lever, and cylinder head engaging means at the outer end of said depressed portion constructed to suspend a cylinder head from the underside of said depressed portion and to swivel the same to permit the cylinder head to swing from a position at right angles to the lever to a position approaching longitudinal alignment with said lever and also to permit tipping of the cylinder head, the parts being so shaped and dimensioned that when the base is rolled in beneath an automobile until the standard lies close to the front fender of the automobile, the lever will extend over the side panel of the hood and the depressed portion of said lever will extend downwardly far enough for its engaging means to engage a cylinder head carried member.

3. A structure as recited in claim 2 wherein the pivotal connection between the bracket and the lever permits endwise movement of the lever with respect to the bracket.

4. A structure as recited in claim 2 wherein the pivotal connection between the lever and the bracket comprises at least one link pivotally connected at one end to the lever at one end of the lever and at its other end to the bracket.

5. A device of the character described, comprising a base consisting of an elongated beam, an inner cross-bar and outer cross-bar, the latter bar being materially longer than the former, cast-
5
er wheels at each end of each bar, a standard sup-
ported upon the base above the beam and cen-
trally of the outer cross-bar, a bracket carried by
said standard and projecting outwardly material-
ly beyond the end of said base, a hydraulic jack,
10 in endwise alignment with and supported upon
the top of said standard, an elongated lever over-
lying said jack and extending in the direction
of the length of said beam, means for pivotally
connecting the outer end of said lever to said
15 bracket, the stem of the jack being movable ver-
tically out of the top of the jack, interengaging
portions between said stem and said lever at a
point upon said lever materially nearer the out-
er end of the lever than the inner end thereof,
the free end portion of the lever being shaped
to provide a part which extends downwardly and
then inwardly to form a terminal end, and means
for suspending a cylinder head from the under-
side of said terminal end in such manner as to
be swiveled with respect thereto so that the
said cylinder head may be swung from a position
substantially at right angles to the lever to a
position in substantial alignment therewith, the 10
proportions of the whole being such that the
lever lies a sufficient distance above the base to
accommodate the fender and side hood panel of
an automobile between itself and the base, with
the terminal end of the lever lying inwardly of 15
and below the top of said panel.
